UNITED STATES PATENT OFFICE.

JOHN LEPINE HANMAN, OF HAMSTEAD, ENGLAND.

ROTARY PUMP AND LIKE MACHINE.

No. 924,773.

Specification of Letters Patent. Patented June 15, 1909.

Application filed June 29, 1908. Serial No. 441,009.

To all whom it may concern:

Be it known that I, JOHN LEPINE HANMAN, a subject of the King of Great Britain, residing at Inglewood Lodge, Hamstead, in the county of Stafford, England, have invented new and useful Improvements in Rotary Pumps and Like Machines, of which the following is a specification.

This invention comprises improvements in rotary pumps and has for its object to increase the capacity of these machines without complicating their construction or increasing their cost.

This invention refers to that type of machine in which two similar rotors are arranged in a casing each carrying projecting wing pistons which rub against the walls of the casing and also recesses for co-acting with such pistons during rotation.

20 The object of my invention is to form a pump of this type but in which the two working members are provided with adjustable rubbing and wearing surfaces covering the whole rubbing area of the pistons, so 25 that the capacity of the pump is very largely increased owing to the more perfect fit obtainable.

In order that the invention may be thoroughly understood and easily carried into 30 practical effect, I have appended hereunto two sheets of drawings illustrating the invention as applied to a rotary pump.

Figure 1 shows a front elevation of a rotary pump constructed according to the invention. Fig. 2 is a side elevation of same. Fig. 3 is a central vertical section on line x—y of Fig. 1. Fig. 4 is a sectional view showing a detachable wearing part which may be arranged on the pistons.

40 The casing a, represents the two cylindrical chambers b, c, in which the rotors e, f, are arranged, each having a corresponding number of pistons g, and a similar number of notches or recesses h. The drawing 45 shows two pistons g, and two notches h, arranged opposite to each other on each of the rotors e, f, and the two rotors are mounted on shafts i, j, at an angle of 90 degrees to each other, thus a piston g, on one synchronizes 50 during rotation with a recess or notch h, on the other. The shaft i, forms the driving shaft and passes through a stuffing box k,

in one of the end plates l, of the casing; the other end of the shaft and both ends of the shaft j, have journal bearings m, in the end plates l, of the casing. The shaft i, is connected through simple spur or other suitable gear with the shaft j, so that when the former is driven through pulley n, the latter is also rotated at an equal speed. During 55 such driving both rotors form working elements as well as valve elements and a suction through opening o, is obtained in chamber b, and in chamber c, and in each chamber as the next piston g, comes round and 60 passes the opening o, a charge of water is carried round and delivered through outlet p; while a fresh suction occurs behind the piston in the two chambers through opening o. 70

This known type of pump as set out is found to possess considerable advantages but owing to the wear of the pistons and the consequent short life of the pump it has not come into practical use. To obviate this 75 wear and to provide a pump whose suction is well maintained during a protracted use, I provide the wing pistons with wearing surfaces made adjustable so that any wear or tendency to clearance between the pistons 80 and the casing can be readily taken up and a thoroughly effective rubbing fit thus permanently obtained. In accordance with the invention I provide each piston with a wearing piece covering the whole rubbing 85 area of the piston. This takes the form of a T or trough piece q, adjustably mounted on the pistons g, by screw pins or bolts r, as shown at Fig. 4.

At Fig. 4, the rubbing surface consists of 90 a T section strip housed in a recess s, running along the piston g. The part u, of the wearing strip q, is slotted and the screw pins r, passing through the walls of the recess s, in the piston also pass through such slots and 95 when drawn tight up exert a grip on the part u, adjacent the slots, thus holding the same. By slackening the screws the wearing piece q, can be varied in its relation to the piston and can be set in the desired position. 100

I claim:—

In combination, a rotatable member for rotary pumps or engines comprising a cylindrical body provided with a recessed carry-

ing projection extending lengthwise of said body, a T-shaped wearing strip having one of its T portions inserted in said recess, and means for clamping the walls of said carrying member on said T inserted portion and adjustably anchoring the same therein.

In testimony whereof I have signed my

name to this specification in the presence of two subscribing witnesses.

JOHN LEPINE HANMAN.
